(57) **CLAIM**

The ornamental design for an insertable beverage container support apparatus, as shown and described.

DESCRIPTION

FIG. 1 is a top perspective view of an insertable beverage container support apparatus showing my new design;
 FIG. 2 is a bottom perspective view thereof;
 FIG. 3 is a front view thereof;
 FIG. 4 is a rear view thereof;
 FIG. 5 is a left view thereof;
 FIG. 6 is a right view thereof;
 FIG. 7 is a top view thereof; and,
 FIG. 8 is a bottom view thereof.
